SUBMERGIBLE HYDROPLANER

Daniel A. Smith, 291 Madrone Ave.,
Santa Clara, Calif. 95051

Filed Nov. 25, 1968, Ser. No. 14,649

Term of patent 14 years

Int. Cl. D12—06

U.S. Cl. D71—1

FIG. 1.

FIG. 4.

FIG. 2.

FIG. 5.

FIG. 3.

FIG. 1 is a top plan view showing the design of the submersible hydroplaner;

FIG. 2 is a side elevational view thereof;

FIG. 3 is a bottom plan view thereof;

FIG. 4 is a front elevational view thereof taken in the direction of the arrows 4—4 in FIG. 2;

FIG. 5 is a rear elevational view thereof, taken in the direction of the arrows 5—5 in FIG. 2.

I claim:

The ornamental design for a submersible hydroplaner, as shown.
